CLAIM

We claim the ornamental design for an inserter handle, as shown and described.

DESCRIPTION

FIG. 1 : is a perspective view of the inserter handle showing the new, original, and ornamental design;

FIG. 2: is a front view thereof;

FIG. 3: is a first side view thereof;

FIG. 4: is a back view thereof;

FIG. 5: is a second side view thereof;

FIG. 6: is a top view thereof; and,

FIG. 7: is a bottom view thereof.

The broken line showing of an inserter handle is for the purpose of illustrating portions of the article and forms no part of the claimed design.
